Primary Examiner—Marianne Pandozzi*(74) Attorney, Agent, or Firm*—Ohlandt, Greeley, Ruggiero & Perle, L.P.(57) CLAIM

The ornamental design for a cup, as shown and described.

DESCRIPTION

FIG. 1 is a front perspective view of a cup showing our new design;

FIG. 2 is a back perspective view of the cup of FIG. 1;

FIG. 3 is a front view of the cup of FIG. 1;

FIG. 4 is a rear view of the cup of FIG. 1;

FIG. 5 is a side view of the cup of FIG. 1;

FIG. 6 is side view of the cup of FIG. 1, opposite the side view of FIG. 5;

FIG. 7 is a top view of the cup of FIG. 1; and,

FIG. 8 is a bottom view of the cup of FIG. 1.

The broken line showing in FIGS. 1 through 7 is for illustrative purposes only and forms no part of the claimed design.
